UNITED STATES PATENT OFFICE.

WALLACE C. LYON, OF HYATTSVILLE, MARYLAND.

NUMBER LICENSE-TAG.

1,168,217.

Specification of Letters Patent. Patented Jan. 11, 1916.

Application filed September 8, 1915. Serial No. 49,593.

To all whom it may concern:

Be it known that I, WALLACE C. LYON, a citizen of the United States, residing at Hyattsville, in the county of Prince George and State of Maryland, have invented certain new and useful Improvements in Number License-Tags; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in number tags and it relates more particularly to tags which are used upon motor vehicles for the purpose of designating the number of the particular machine to which the tag is attached.

The invention has for its object the provision, in combination with the number tag, of an independent interchangeable date plate adapted to be readily attached to the number tag, the date plate being preferably of a color contrasting with the color of the tag to which it is attached.

To this end and to such others as the invention may pertain the same consists in the peculiar arrangement, combination, and adaptation of parts, all as more fully hereinafter described, shown in the accompanying drawings and then specifically defined in the appended claims.

The invention is clearly illustrated in the accompanying drawings, which, with the numerals of reference marked thereon, form a part of this specification and in which drawings—

Figure 1 is a plan view of a number tag constructed in accordance with my invention. Fig. 2 is an enlarged detail showing the seal used in securing the date plate to the tag. Fig. 3 is a plan view of the date plate. Figs. 4 and 5 are enlarged detailed sections showing the means of attaching the plate to the tag. Fig. 6 is an enlarged side view of a soft metal rivet employed in securing the date plate to the number tag.

Reference now being had to the details of the drawings by numerals, 1 designates the number tag such as commonly employed for designating the number of the motor car or other vehicle to which the tag is attached, together with an indication of the state and

the date or year for which the tag is issued. This number tag is of metal and the background as well as the colors of the numbers thereon are subject to regulations imposed by the state authorities, it being customary to change the colors from year to year in order that the color of the tag or figures contained thereon may indicate at once, the year for which the tag was issued.

An essential object of the present invention resides in the provision of means whereby the number tags may be used continuously and, providing an independent plate having a background of a color contrasting with the color of the tag to which it is attached, which plate can be readily detachably affixed to the face of the number tag and secured thereto by an official seal, the breaking of which seal would be necessary, in removing the plate from the number tag.

2 represents the date plate which, if desired, can be made reversible having its opposite sides provided with different dates. The said date plate 2 is provided with openings 3, 3, one of which openings is so positioned as to register with a like opening formed in the number tag, to which it is attached, the other opening 3 being so positioned as to cause the same to register with the opening in the number tag when the plate is reversed, so as to present the opposite side of the plate, as will be readily understood.

4 is a keeper designed to receive one of the corners of the date plate. This keeper is integral with the number tag and the struck-up therefrom as shown clearly in Fig. 1 of the drawings. The date plate having been placed in position with one of its corners 95 locked with the struck-up keeper 4, is secured to the number tag by means of a soft metal rivet 5 passed through the registering openings in the number tag and plate respectively as indicated at 6 and, is headed 100 upon the face of the date plate and rear face of the number tag as indicated in Fig. 4 of the drawings. The heads of the rivet upon both of its ends have impressed thereon the official seal of the State. And as it will be 105 at once noted this official seal must be destroyed should an attempt be made to remove the plate from the number tag and the breaking of the seal would of course indicate at once that the plate had been removed or 110 that an attempt had been made to remove it.

From the foregoing description of the con-

struction and assemblage of the parts, the use of the invention and the advantages gained thereby will be at once evident. It is the universal custom of the various States 5 to furnish the owners of motor vehicles which are required by law to be taxed, with a number tag, this said tag indicating the tax has been paid and that all requirements of the law have been complied with and 10 indicating the number of the particular vehicle to which the tag is attached. In addition to indicating the number, the tag also indicates the State in which the license is obtained and also the year for which the 15 license has been granted. The face of the number tag has a background of a distinctive color decided upon, for the year for which the tag is to be used and, it has heretofore been customary in order to determine 20 the year for which the tag is issued to require that the numbers or figures displayed upon the face of the tag should be subject to regulations as to color, size, etc., and, it has accordingly been found necessary 25 to remove the tag at the end of the fiscal year for which the license was paid and to substitute therefor a number tag of a different color both as to background and indicating numbers, letters, etc., thereon.

30 As the furnishing of tags from year to year has necessarily involved (in view of the great number of tags issued), a very great expense, it will be at once noted that, by indicating the date upon a separable plate, 35 having a background of a color contrasting with the background of the number tag so as to indicate by reason of this contrast in colors, the year for which the tag was issued, that the number tag can be used for an 40 indefinite period, the expense involved by the State, in renewing the tag from year to year, after the initial expense involved in the purchase of the number tag would be reduced to the nominal cost of the date 45 plates. It will also be noted that, in case

the date plates are provided with dates upon the opposite sides, that the same date plate can be used for two successive years, it being simply necessary that the plates should be removed and reattached to the number 50 tag so as to present the opposite face of the plate. The official seal of the State being employed in securing the plate to the tag, and the impression of the seal being upon both ends of the rivet, adequate provision is 55 had against the unauthorized removal of the date plate from the tag.

Having thus described my invention, what I claim to be new and desire to secure by Letters Patent is:—

1. A main plate having a fixed color and bearing identification characters, in combination with an auxiliary plate, the opposite faces of which are of different colors and both differing from the color of the main 65 plate and each of the faces bearing a fiscal date, said auxiliary plate being adapted to be superimposed upon and secured in contact with the main plate so as to present one of the fiscal dates upon the auxiliary 70 plate, substantially as described.

2. A main plate having a fixed color and bearing identification characters, in combination with an auxiliary plate, the opposite faces of which are of different colors and 75 both differing from the color of the main plate and each of the faces bearing a fiscal date, said auxiliary plate being adapted to be superimposed upon and permanently secured in contact with the main plate so as 80 to present either of the fiscal dates upon the auxiliary plate, substantially as shown and described.

In testimony whereof I hereunto affix my signature in presence of two witnesses.

WALLACE C. LYON.
